FEELER MECHANISM FOR LOOMS

Application filed November 26, 1929. Serial No. 409,969.

This invention relates to feeler mechanism for looms whereby the operative condition of the loom is changed from time to time as by replenishment of filling.

5 The amount of filling remaining upon the filling carrier or bobbin when it is ejected from the shuttle constitutes waste and is largely dependent upon the sensitiveness of the feeler either to the presence of filling in 10 the shuttle or its substantial absence.

One of the objects of the present invention is to provide a feeler mechanism of the side slipping type wherein the feeler shall be sensitive both to the presence and absence of filling and is caused to side slip by the forward pressure upon the feeler when the filling is substantially exhausted. More specifically stated, the invention provides a side slipping feeler pivotally mounted upon a link 15 and normally under the influence of a spring connected to the feeler between the pivotal points of the link and exerting a rearward stress or pull upon the feeler to thereby move both the link and the feeler rearwardly and 20 swing the feeler laterally into its filling feeling position.

The constant recurring contacts of the feeler with the filling on detecting beats is liable to injure the filling, and another aspect of the invention therefore provides that the feeler shall be held in a frontward inoperative position out of contact with the filling for periods of time and then released for 30 its active period, so that the feeler will contact with the filling only at intervals. With respect to this feature of the invention, the feeler and link are held in front position by a detent which acts upon the feeler in connection with the rearwardly pulling spring to 35 move the feeler laterally so that the tip end of the feeler will not engage the filling during periods of inactivity of the feeler.

The invention and novel features thereof will best be made clear from the following description and the accompanying drawings of one good form thereof.

In the drawings:

Fig. 1 is a perspective view showing portions of the loom and a feeler mechanism containing the present invention;

Fig. 2 is a plan view showing the feeler in active position;

Fig. 3 is a similar view showing the feeler as having been moved frontwardly by a working supply of filling on a detecting beat and the detent in position to engage and hold the feeler in frontward position; 55

Fig. 4 is a similar view showing the feeler as held by the detent in its frontward inactive position; 60

Fig. 5 is a detail section on the line 5—5 of Fig. 2;

Fig. 6 is a plan view showing the feeler in active position and the filling substantially exhausted; and 65

Fig. 7 is a similar view showing the feeler as having been laterally displaced by the forward pressure of a surface within the shuttle to thereby call for replenishment of filling. 70

The replenishing mechanism is not herein shown and described because the details thereof form no essential part of the present invention and such replenishing mechanism is now well understood in the art. 75

The loom frame may be of usual construction, and mounted upon the breast beam 2 is the transverse or rock shaft 3 having the upwardly extending arm 4 to which is pivotally connected at 5 the actuator 6, the front movement of which is utilized for initiating replenishment of filling. 80

The shipper stand 7 has a lateral extension 8 to which a bracket 9 is secured, constituting a support for the feeler stand 10. 85 As shown, the bracket 9 is susceptible of adjustment by means of the bolt 11 and slot 12, and the feeler stand 10 is secured to the bracket 9 by a bolt 13. The parts so far described may be of usual construction and need no further explanation. 90

Pivots connected to the feeler stand at 14 at one side of the longitudinal axis of the feeler is a link 15, the other end of which is pivotally connected at 16 to a laterally extending arm 17 projecting from the feeler 18, the pivotal connection 16 being at the opposite side of the longitudinal axis of the feeler from that of the pivot 14. 95

The feeler 18 has the filling engaging tip 100

portion 19 which is preferably provided with teeth 20 for engagement with the filling, and in order that the feeler may enter the shuttle to feel for the filling the shuttle box is provided with the usual opening 21 in the front wall thereof which registers with a similar opening 22 in the front wall of the shuttle 23 when the latter is in the detecting box. The shuttle may be of the usual automatically threading type now well understood.

Connected to the feeler between the pivotal points 14 and 16 of the link 15 is a spring 24, one end of which may be engaged with 15 the pin 25 and its other end secured at the rear of the feeler stand, as indicated in Figs. 2 and 3, the result being that both the link 15 and the feeler 18 are normally under the rearward pull or stress of the spring 24 to move 20 both of these parts rearwardly, and a stop 26 extends upwardly from the feeler stand to limit the rearward movement of the link under the stress of the spring 24.

From the construction thus far described 25 it will be noted that the single pull spring 24 being connected to the feeler between the pivotal points of the link will act with a pulling effect rearwardly and also act upon the feeler to move it laterally into feeling 30 position.

When the link and the feeler have been moved rearwardly, as hereinbefore described, and the feeler is under the stress of the spring 24 to swing it laterally on the link, it 35 is desirable that the swinging movement of the feeler shall be limited, and to this end the pin 25 to which the end of the spring 24 is secured, is extended downwardly through the feeler, as at 27, Fig. 5, in position to engage the front edge portion of the link 15 to thereby limit swinging movement of the feeler on the link. When the feeler is in its rearward feeling position, the link 15 bears against the stop 26 to limit further rearward 40 movement of both the link and the feeler, and the lower end portion 27 of the pin 25 engages the link to thereby limit the lateral movement of the feeler into its feeling position under the stress of the spring 24.

50 From the construction described it will be apparent that the feeler and link are under the influence of a single spring which exerts a rearward pull upon the feeler to move the parts into position as hereinbefore described, 55 and since the function of the spring is as stated, its stress may be made light and sensitive, with the result that when a working supply of filling is present in the shuttle on a detecting beat, the feeler and link may be 60 moved forwardly in opposition to the rearward stress of the spring and the teeth of the feeler will prevent side slipping movement thereof. When, however, the filling has become substantially exhausted and is no 65 longer sufficient to prevent side slipping

movement of the feeler, the latter will side slip into the position indicated in Fig. 7 against the light stress of the spring 24, with the result that the feeler is extremely sensitive, both as to presence and substantial absence of filling. 70

During the weaving operation it is desirable that the feeler may be held in a frontward position out of contact with the filling on detecting beats and then released to its 75 feeling function periodically, and another aspect of the invention therefore provides means for accomplishing these results.

The feeler 18 is provided with a detent 80 engaging notch 28, and pivotally connected at 29 is a detent 30, the downturned end portion 31 of which is adapted to engage the holding notch 28 in the feeler when the latter is moved frontwardly by a working supply of filling on a detecting beat. The detent 30 85 is normally under the influence of yielding means to move it downwardly to cause the end 31 thereof to engage the notch 28 in the feeler, and to this end the spring 24 has its rear portion at 32 connected to the detent. 90

The relation of the pivoted link 15 and the feeler, as hereinbefore described, and the connection of the spring 24 with the feeler between the pivotal points of the link, have the effect of causing the feeler to be 95 moved laterally, as indicated in Fig. 4, when the detent is engaged with the holding notch 28 of the feeler, so that the feeler is displaced laterally by the detent when it is in inoperative position, thereby removing the tip 100 of the feeler from engagement with the filling during the inactive periods of the feeler.

The transmitter and its cooperative relation with the feeler is of novel construction and comprises a rocking member or shaft 33, 105 the end portion remote from the feeler being mounted at 34 in the actuator 6, while the end adjacent the feeler is mounted for rocking movement in a bracket 35 rising from or secured to the feeler stand 10. The bearing of the transmitter 33 in the bracket 35 is sufficiently loose to permit the transmitter 33 to be moved frontwardly and rearwardly the necessary amount required by the frontward and backward movement of the actuator 6, 110 and to prevent endwise movement of the transmitter 33 the stops 36 are secured to the transmitter 33 at each side of the bracket 35, as indicated.

The cam follower 37 is actuated as usual 115 from the lower or cam shaft and has a top portion 38 provided with a forward extension 39 and a shoulder 40, the latter being utilized to effect frontward movement of the actuator 6 through the transmitter when filling replenishment is to be initiated.

Secured to the transmitter 33 adjacent the actuator 6 is a lug or sleeve 41 from which extends frontwardly the bail or loop 42 normally resting upon the frontward extension 120

39 of the cam follower and adapted for engagement by the shoulder 40 when in its normal position, to thereby move the actuator 6 frontwardly and effect replenishment of filling.

5 The end of the transmitter adjacent the feeler is provided with a downwardly extending arm 43 which extends through an opening 44 formed in the side of the feeler, so that the downwardly extending arm 43 is between the lateral arm 17 and the projection or finger 45 at the side of the feeler.

10 When the feeler is in its rearward feeling position, as indicated in Figs. 1 and 2, the weight of the arm 43 and the bail 42 causes 15 the transmitter to remain in operative relation with the cam follower, so that on a detecting beat with a working supply of filling in the shuttle, as indicated in Fig. 2, the 20 forward movement of the feeler will cause the finger 45 thereof to turn the transmitter and lift the bail 42 from its operative position so that when a working supply of filling is 25 present in the shuttle on a detecting beat and the feeler is in feeling position, the latter will be moved frontwardly to turn the transmitter and move the bail 42 thereof out of 30 operative position. When, however, the filling is substantially exhausted, as indicated 35 in Figs. 6 and 7, on a detecting beat, the feeler will side slip, as indicated in Fig. 7, and fail to turn the transmitter from its 40 operative position, thereby causing the shoulder 40 of the cam follower to engage the bail 42 of the transmitter and move the actuator 6 frontwardly to effect replenishment of filling. When the feeler is held in its front- 45 ward inoperative position, as indicated in Fig. 4, the downwardly extending arm 43 of the transmitter will be engaged by the finger or projection 45 of the feeler and cause the transmitter to be turned sufficiently to raise the bail 42 out of the path of movement of the shoulder 40 of the cam follower and the loom will continue to run without filling 50 replenishment during the period of inactivity of the feeler.

55 As hereinbefore indicated, it is desirable to free the feeler from time to time that it may move to rearward feeling position to thereby detect the condition of the filling in the shuttle, and as one means to this end the detent 30 is under control of a trip device which acts periodically to trip the detent from holding engagement with the feeler.

In the present instance of the invention, the trip device comprises a chain 46 which passes about sprocket wheels 47 and 48, the latter of which is actuated through a train of mechanism connected to a going part of the loom, as, for instance, the take-up. In the present instance, the take-up shaft 49 is driven from the under or cam shaft 50 and operatively engaged with the sprocket 48 through a train 60 of mechanism 51 which may be of any usual

type, so that during the loom operation the sprocket chain 46 will be moved progressively.

Connected to the sprocket chain 46 is a lug or projection 52 adapted to engage a roller or weight 53 carried by a bell crank lever 54 pivotally mounted at 55 on the downwardly extending arm 56, the lower end of which provides a bearing 57 for the sprocket wheel 47.

Connected to the arm 58 of the bell crank 54 is a link 59, the upper end portion of which is engaged with the end 60 of the detent, with the result that when the projection 52 passes under the roll or weight 53 the detent will be tripped to free the feeler to its active position, as indicated in Fig. 1. Should the feeler detect a working supply of filling in the shuttle and consequently be moved frontwardly thereby after the projection 52 has passed from the roll or weight 53, the detent will be released to again engage the holding notch 28 of the feeler to maintain the latter in frontward inactive position. Should the feeler, however, detect approaching exhaustion of filling and consequently be not moved 90 frontwardly sufficiently far for the detent to engage the holding notch of the feeler, the end 31 of the detent will rest upon and ride on the flat top surface of the feeler, as indicated in Fig. 7, so that the feeler will remain 95 active and call for a change of filling when it side slips.

From the construction described it will be noted that the present invention provides a 100 feeler which is very sensitive both to the presence and absence of filling in the shuttle so that the amount of waste is minimized.

What is claimed is:

1. In a feeler mechanism for looms, the combination of a feeler stand, a side slipping filling feeler having at its front portion a laterally extending portion, a link pivotally mounted on the feeler stand at one side of the longitudinal axis of the feeler and pivotally connected to the laterally extending portion of the feeler at the other side of its longitudinal axis, a spring connected to the feeler between the pivotal points of the link and exerting a rearward pull upon the feeler to move both the link and feeler to rearward feeling position and swing the feeler laterally about its pivotal connection with the link, and a stop to prevent the feeler being moved laterally beyond its feeling position by the spring.

2. In a feeler mechanism for looms, the combination of a feeler stand, a side slipping filling feeler having at its front portion a laterally extending portion, a link pivotally mounted on the feeler stand at one side of the longitudinal axis of the feeler and pivotally connected to the laterally extending portion of the feeler at the other side of its longitudinal axis, a spring connected to the feeler between the pivotal points of the link and ex-

erting a rearwardly inclined pull upon the 5
feeler to move the link into its rearward position and turn the feeler on its pivotal connection with the link, and a stop mounted on the feeler for engagement with the link when in rear position to prevent the feeler from lateral swinging movement by the spring beyond its feeling position.

3. In a feeler mechanism for looms, the 10
combination of a feeler stand, a side slipping filling feeler having a laterally extending portion provided with a slot, a link pivotally mounted on the feeler stand at one side of the longitudinal axis of the feeler and pivotally connected to the laterally extended portion of the feeler at the opposite side of the longitudinal axis of the feeler, a spring connected to the feeler between the pivotal points of the link and to another part rearward of the link to exert a rearward pull 15
upon the feeler and link to move both into rearward feeling position, and a transmitter having an arm extending into the slot of the laterally extending portion of the feeler to 20
initiate replenishment of filling when the feeler side slips on a detecting beat.

4. In a feeler mechanism for looms, the 25
combination of a transmitter normally positioned for initiating replenishment of filling, a feeler stand, a side slipping filling feeler having a laterally extending arm, a link pivoted at one end to the feeler stand and to the laterally extending arm at its other end, a spring connected to the feeler and exerting 30
a rearward pull upon the feeler to move the link and feeler to rearward feeling position, a projection mounted on the feeler for engagement with the transmitter when the feeler is moved frontwardly by a working supply of filling to thereby move the transmitter 35
from its normal position and prevent replenishment of filling until the feeler side slips on a detecting beat.

5. In a feeler mechanism for looms, the 40
combination of a feeler stand, a side slipping filling feeler, a link having one end pivotally mounted on the feeler stand and its other end pivotally connected to the feeler, a spring connected at one end to the feeler between the 45
pivotal points of the link and exerting a rearward pull upon the feeler to move both the link and feeler to rearward feeling position and swing the feeler laterally on its pivotal connection with the link, a detent for holding 50
the feeler and link in a frontward inoperative position, and a trip for periodically freeing the feeler and link from the detent that the spring may move the feeler and link rearwardly and turn the feeler upon its pivotal connection with the link into feeling position.

6. In a feeler mechanism for looms, the 55
combination of a feeler stand, a side slipping filling feeler, a link having one end pivoted on the feeler stand and its other end pivoted to the feeler, a spring connected to the feeler

between the pivotal points of the link and exerting a rearward pull upon the feeler and link to pull the link and the feeler to rearward feeling position, a detent for holding the feeler and link in a frontward inoperative position out of contact with the filling on detecting beats, a transmitter normally positioned to initiate replenishment of filling and held from said position by the feeler when it and the link are held in frontward inoperative position during the periods of inactivity of the feeler, means for freeing the feeler and link from the detent periodically that the feeler and link may be moved rearwardly by the spring and the transmitter may move to its normal position for initiating replenishment of filling should the feeler detect substantial exhaustion of filling and partake of its side slipping movement.

7. In a feeler mechanism for looms, the 85
combination of a stationary support, a swinging carrier pivoted to the support for movement towards and from the front of the loom, a side slipping feeler pivotally mounted on the swinging carrier and having a filling engaging portion off-set from the pivot of the feeler to move along and in contact with a substantially exhausted supply of filling on a detecting beat, and a single resilient element 90
directly connected to the side slipping feeler at a point to one side of the pivotal connection of the feeler with the swinging carrier to move both the feeler and the swinging carrier rearwardly solely by the action of the single resilient element.

8. In a feeler mechanism for looms, the 100
combination of a feeler stand, a side slipping filling feeler, a link having one end pivotally mounted on the feeler stand and its other end pivotally connected to the feeler, a spring connected at one end to the feeler between the pivotal points of the link and exerting a rearward pull upon the feeler to move both the link and feeler to rearward feeling position and swing the feeler laterally on its 110
pivotal connection with the link, a detent for engaging the feeler to hold the feeler and link in a frontward idle position with the feeler in an inclined position to prevent engagement by the filling, and a trip for the detent 115
to periodically free the feeler and consequently the link that the spring may move the feeler and link to rearward feeling position.

9. In a feeler mechanism for looms, the 120
combination of a feeler stand, a side slipping filling feeler, having a lateral extension, a link pivotally mounted at one end on the feeler stand and having its other end pivotally connected to the lateral extension of the feeler, a pull spring connected to the feeler between the pivotal points of the link to effect movement of the link and feeler to rearward feeling position, a stop for limiting the rearward movement of the link, and a stop for limiting the lateral swinging movement 125

of the feeler on the link into feeling position.

10. In a feeler mechanism for looms, the combination of a feeler stand, a side slipping filling feeler having a lateral extension, a link pivotally mounted at one end on the feeler stand and having its other end pivotally connected to the lateral extension of the feeler, a pull spring connected to the feeler between the pivotal points of the link to effect movement of the link and feeler to rearward feeling position, a stop for limiting the rearward movement of the link, and a stop for limiting the lateral swinging movement of the feeler on the link into feeling position, a detent for holding the feeler and link in a forward inoperative position for a plurality of detecting beats, and means for periodically freeing the detent from the feeler that the spring may move the link to rearward position and the feeler laterally to feeling position.

In testimony whereof, I have signed my name to this specification.

PATRICK F. O'BRIEN.
